Filed Sept. 14, 1962, Ser. No. 71,702

Term of patent 7 years

(Cl. D48—4)

FIG. 2

FIG. 1

FIG. 1 is a side elevational view of a wall hanging lamp embodying our new design, with the cord broken away in part to indicate indeterminate length, and with a fragmentary wall surface shown for illustrative purposes only.

FIG. 2 is a top plan view thereof as shown in FIG. 1.

The undisclosed side is a mirror image of the side shown.

The dominant features of our design reside in the portions shown in full lines.

We claim:

The ornamental design for a wall hanging lamp, as shown and described.
